CLAIM

The ornamental design for a picnic table, as shown and described.

DESCRIPTION

FIG. 1 is a perspective view of a picnic table showing my design;

FIG. 2 is a top plan view thereof on a reduced scale; FIG. 3 is an elevational view thereof showing one of the two identical sides; and

FIG. 4 is an end elevational view of the picnic table shown in FIG. 2, the undisclosed end being a mirror image thereof.
